UNITED STATES PATENT OFFICE

149,808

DESIGN FOR A MANICURIST'S KIT

Billie B. Gaitskill, Los Angeles, Calif.

Application November 21, 1946, Serial No. 134,991

Term of patent 7 years

(Cl. D86—10)

To all whom it may concern:

Be it known that I, Billie B. Gaitskill, a citizen of the United States, residing at Los Angeles, in the county of Los Angeles and State of California, have invented a new, original, and ornamental Design for Manicurist's Kit, of which the following is a specification, reference being had to the accompanying drawing, forming part thereof, in which:

Fig. 1 is a top plan view of a manicurist's kit, showing my new design;

Fig. 2 is a rear side elevation;

Fig. 3 is an elevation of the opposite side of the kit;

Fig. 4 is an end elevation;

Fig. 5 is a perspective view of the kit, showing the compartment covers in open positions.

I claim:

The ornamental design for a manicurist's kit, as shown.

BILLIE B. GAITSKILL.
